LINE SPACE MECHANISM FOR RECORD
MAKING MACHINES

Elmer L. Wise, Bridgeport, Conn., assignor to
Underwood Elliott Fisher Company, New York,
N. Y., a corporation of Delaware

Application June 16, 1938, Serial No. 214,009

13 Claims. (Cl. 197—124)

This invention relates to record making machines such as typewriting machines, adding machines and calculating machines in which a typed record is made in successive lines of a record sheet.

One object of the invention is to provide record making machines with novel and improved mechanism for operating the line space mechanism at the end of the return movement of the carriage.

Another object of the invention is to produce, for such machines, a novel and improved mechanism for operating the line space mechanism during the latter part of the return movement of the carriage and for locking the line space mechanism in position.

Another object of the invention is to provide machines of the above class with novel and improved mechanism for releasing or unlocking the line space mechanism under certain conditions.

Another object of the invention is to produce, for record making machines, a novel and improved mechanism for unlocking the line space mechanism during the next advance movement of the carriage following the actuation and locking of said mechanism.

The present machine is provided with power mechanism for actuating the line spacing mechanism and another object of the invention is to provide machines of this class with novel and improved mechanism for unlocking the line space mechanism upon throwing in the power mechanism to actuate the line space mechanism by power.

With the above and other objects in view the invention comprises a machine embodying the novel and improved features, constructions and combinations of parts hereinafter described and particularly pointed out in the claims, the advantages of which will be readily understood and appreciated by those skilled in the art.

The various features of the invention will be readily understood from the accompanying drawings illustrating the invention in its preferred form and the following detailed description of the constructions therein shown.

In the drawings:

Fig. 1 is a view in vertical section illustrating certain portions of a typewriting machine of the Elliott Fisher type having the invention applied thereto;

Fig. 2 is a plan view of a portion of the machine with the carriage and certain other parts removed;

Fig. 3 is a perspective view looking from the rear of the machine and illustrating particularly the power operated mechanism for moving the line space frame forwardly and rearwardly on the platen frame;

Fig. 4 is a detail view in front elevation partly broken away and partly in section illustrating a portion of the mechanism for actuating the line space frame from the type carriage during the last part of the carriage return movement and showing the parts in their normal positions,

Fig. 5 is a view similar to Fig. 4 illustrating the parts in the position which they assume at the end of the return movement of the carriage,

Fig. 6 is a view in side elevation partly broken away and illustrating certain parts of the line space mechanism in the positions which they assume at the end of the return movement of the carriage,

Fig. 7 is a view similar to Fig. 5 with certain parts omitted to show the structure more clearly, and illustrating the mechanism with the parts substantially in the positions which they assume at the end of the first escapement movement of the carriage following the carriage return,

Fig. 8 is a view similar to Fig. 6 illustrating the parts in the positions which they assume at a point in the operation of the machine immediately after the first escapement movement of the carriage,

Fig. 9 is a detail plan view illustrating the control shaft of the means for operating the line space mechanism by power and the centering mechanism for said shaft with the parts in the positions which they assume when the shaft has been shifted in a right hand direction,

Fig. 10 is a view similar to Fig. 7 illustrating the parts in the positions which they assume when the control is shifted to the right as in Fig. 9,

Fig. 11 is a view similar to Fig. 9 showing the parts in the positions which they assume when the control shaft is shifted in a left hand direction, and

Fig. 12 is a view in front elevation illustrating the mechanisms shown in Figs. 9 and 10 with the parts in the positions which they assume when the control shaft is shifted to the left as in Fig. 11.

The invention is illustrated in this application as applied to a machine of the type illustrated and described in the patent to Foothorap, No. 1,904,127 dated April 18, 1933, and many of the parts have substantially the same construction as the corresponding parts of the machine illustrated and described in said patent.

The machine illustrated in the present application comprises a platen frame provided with side rails or bars 2 connected by transverse bars, one of which is indicated at 4, and a substantially flat platen 6 mounted for vertical movement in said frame. Upon the side rails of the platen frame is supported a line space frame movable forwardly and rearwardly on said rails to line space the type carriage with relation to

the platen. The line space frame comprises side brackets or bars 8 connected by front and rear rails of which the rear rail only is shown in this application and is indicated at 10. The line space frame is provided with wheels or rollers 12 which engage respectively the upper edges of the rails 2 of the platen frame to enable the line space frame to be moved readily over the platen frame.

The mechanism for moving the line space frame comprises a shaft 14 rotatably mounted in bearings formed on said frame, the shaft extending substantially parallel with the front and rear rails of the frame. Upon the shaft are fixed gears 16 which mesh with the teeth of racks 18 secured to the side rails 2 of the platen frame. The shaft is given a predetermined angular movement in a counter-clockwise direction, Figs. 6 and 8, at the end of the return movement of the carriage to impart a line space movement to the line space frame.

The type carriage, a portion of which is illustrated in Fig. 1 and indicated at 20, is provided with wheels or rollers 22 which engage the upper edges of the front and rear rails of the line space frame so that the carriage is movable transversely of the machine along said rails to impart forward and return movements to the carriage. The carriage is connected by a flexible band 23 to the usual spring drum 25 which tends constantly to draw the carriage in a right hand direction across the machine.

The machine embodying the present invention is preferably provided with a key and carriage controlled automatically operating mechanism for imparting return movements to the type carriage as is shown and described in the above Foothorap patent.

The mechanism for turning the shaft 14 to actuate the line space frame comprises a wheel 26 attached to one end of said shaft and having a series of fine teeth on its periphery which are engaged at intervals by a pawl 28 pivoted at 30 on a pawl carrier 32 mounted to turn on the shaft. A pawl actuating bell crank 34 is also pivoted on said shaft and is provided with a pin or stud 36 on one arm thereof engaging in a slot 38 in the outer portion of the pawl. The pivotal movement of the pawl 28 with relation to the pawl carrier 32 is limited by means of a pin 40 projecting from the pawl carrier and engaging in a recess 42 in the lower portion of the pawl. The pawl carrier and the pawl actuator are acted upon respectively by coiled springs 44 which tend to swing the carrier and actuator in a clockwise direction (Figs. 6 and 8). The pawl carrier and pawl actuator are normally held substantially in the position shown in Fig. 8 with the pawl in engagement with a stop 46 on the line space frame and the pawl is thereby held out of engagement with the toothed wheel 26.

In actuating the toothed wheel, the pawl actuator 34 is swung in a counter-clockwise direction Figs. 6 and 8. During this movement of the actuator the pawl is first engaged with the toothed wheel and the pawl carrier and toothed wheel are then turned with the pawl actuator until the movement of the pawl is arrested. The movement of the pawl is arrested to limit the line space movement by means of a stop pin 48 mounted on a bracket 50 attached to the line space frame and arranged to engage the forward side of the pawl as shown in Fig. 6. The engagement of the pawl with the toothed wheel

26 after the movement of the pawl is arrested, locks the line space frame in position.

The pawl actuator is swung in counter-clockwise direction Figs. 6 and 8 to actuate the shaft 14 to impart a forward movement to the line space frame just before the completion of each return movement of the carriage from the movement of the carriage.

All of the parts of the machine above described preferably have substantially the same construction, arrangement and mode of operation as the corresponding parts of the machine illustrated and described in the Foothorap patent referred to above.

The mechanism for actuating the pawl actuator 34 from the carriage will now be described. The other arm of the pawl actuator is connected by a link 52 with one end of a lever 54 secured to the rear end of a rock shaft 56 mounted in bearings in the line space frame and extending toward the front of said frame. The other end of said lever is connected by a link 58 with an arm 60 secured to the rear end of a relatively short rock shaft 62 also mounted in bearings in the line space frame. To the forward end of the shaft 62 is secured an arm 64 which is connected by means of a coiled spring 66 with the lower arm of a lever 68 pivoted to turn freely on the forward end of the shaft 62. The upper arm of the lever 68 is provided with a forwardly turned contact flange 70 which is arranged to be engaged by a pin 72 carried at the left hand end of an actuating pawl or dog 74 pivoted on a stud 76 secured upon a plate 78 forming a slide mounted on the line space frame and movable transversely of said frame. The dog 74 is acted upon by a coiled spring 80 which tends to swing the left hand end thereof downwardly to carry the pin 72 into operative position with relation to the contact flange 70 on the lever 68, the movement of the pawl under the action of the spring being limited by means of a pin 82 projecting from a plate 84 secured to the slide 78 in spaced relation thereto as shown in Fig. 2.

During the entire movement of the carriage, except the first part of the advance movement and the last part of the return movement thereof, the slide 78 is held substantially in the position shown in Fig. 4. After the first part of the advance movement of the carriage and during the entire return movement thereof, the dog 74 is maintained by the spring 80 substantially in the position shown in said figure. As the carriage executes the last part of its return movement, the slide 78 is moved to the left with the carriage and through the engagement of the pin 72 on the dog 74 with the contact flange 70 on the lever 68 the lever is actuated to impart a line spacing movement to the pawl carrier 26 through the connections described. During the first part of the advance movement of the carriage, slide 78 is moved back to the right to its normal position shown in Fig. 4. The slide 78 is provided with parallel guide slots 86 and 88 in which engage respectively a guide stud 90 and the shaft 62 and the plate is held in position on the guide stud and shaft by means of holding plates or washers 94 and 96. The movement of the slide 78 toward the left is stopped by the engagement of the left hand end of a projection or beak 95 on the slide with a fixed stop 97 rigidly secured to the right hand end of the rear rail 10.

The mechanism for moving the slide to the left from the position shown in Figs. 1 and 4 during the last part of the return movement of the

carriage comprises a draft rod 98 similar in construction and mode of operation to that shown in Foothorap Patent 1,904,127, which extends transversely of the line space frame in a channel formed by the front face of the rear rail 10, and rear face of the carriage escapement rack 100. The right hand end of the draft rod 98 is connected by means of an attaching plate 102 to the slide 78. The left hand end of the draft rod is attached by means of a box nut 99 to a laterally bent portion of a guide plate 101 provided with slots 103 in which engage headed fastenings 105 threaded into the carriage escapement rack, this guide plate moving longitudinally with the draft rod during the longitudinal movement of said rod. A spring 107 anchored at one end to the fixed stop 97 and connected at its opposite end to the draft rod 98 yieldingly retains slide 78 and the draft rod at their right hand limits of travel as determined by contact of the left end wall of the slot 86 with the guide stud 90.

The left hand end portion of the draft rod 98 is provided with teeth upon its upper face and upon the draft rod are mounted a series of arresters 104, 106 and 108 of different heights engaging said teeth and adjustably arranged on the rod at different distances from the left hand end thereof. The arrester 104 having the greatest height and located nearest the left hand end of the draft rod is arranged to be engaged by the abutment plate 110 secured to the carriage 20 to arrest the carriage at the end of a full return movement thereof. The arresters 106 and 108 are arranged to be engaged alternatively by means of a check stop 112 mounted on the carriage and protrudable to different positions to engage selectively the said arresters at different points in the return movement of the carriage. Thus the return movement of the carriage will be arrested with the carriage in different positions respectively by the engagement of the abutment 110 with the arrester 104 and by the engagement of the protrudable check stop 112 with the arresters 106 and 108.

As the carriage approaches the end of its return movement the abutment 110 on the carriage engages the arrester 104 or the check stop 112 engages one of the arresters 106 and 108 and the draft rod is moved to the left with the carriage thereby carrying the slide 78 therewith and the carriage is finally arrested by the engagement of the projection 95 on the slide with the stop 97 which arrests the movement of the slide and the draft rod. During this movement of the slide the line space mechanism is actuated through the mechanism described to impart a movement to the line space frame.

When a line space movement has been imparted to the line space frame, the movement of the frame is stopped by the engagement of the line space pawl 28 with the stop pin 48 to prevent overrunning of the frame and the frame is locked by the engagement of the pawl with the toothed wheel 26. As is well-known to those familiar with this type of machine, it is desirable to unlock or release immediately the line space frame at the very beginning of the advance movement of the carriage. With the present construction the dog 74 is lifted to disengage the pin 72 from the lever 68 during the first escapement movement of the carriage.

The present machine is provided with the usual power actuated mechanism controlled by a pair of spaced knee levers for moving the line space frame forwardly or rearwardly over the platen.

Since this mechanism may be thrown into operation at the time that the carriage is at the limit of its return movement when the line space frame is locked by the line space mechanism, a control is provided by which the line space frame is unlocked before this mechanism is thrown into operation. This control mechanism operates to swing the dog 74 upwardly to disengage the pin 72 from the lever 68 prior to the engagement of the clutch in the drive for actuating the line space frame from the motor.

The mechanism for swinging the actuator dog 74 upwardly to disengage the pin 72 from the lever 68 comprises a cam carrier 114 in the form of a lever pivoted on the shaft 62. This cam carrier is normally held in the angular position on the shaft shown in Figs. 1 and 4. The cam carrier 114 is provided with a cam face 116 arranged to engage a pin 118 projecting forwardly from the dog 74 when the parts are in the positions which they assume at the end of the return movement of the carriage as shown in Fig. 5. Pivoted at 120 on the cam carrier 114 is a cam dog 122 provided with a cam face 124 also arranged to engage the pin 118 when the parts are in the position shown in Fig. 5. The cam dog is acted upon by a coiled spring 126 which normally maintains the dog in the position shown in Fig. 5 with relation to the cam carrier, with an arm on the dog then engaging the pin 128 fixed to the cam carrier to limit the movement of the dog with relation to said carrier.

When the carriage is in any position except at or near the limit of its return movement, the parts occupy substantially the positions shown in Figs. 1 and 4 with the actuating dog 74 in depressed position and with the pin 118 on said dog some distance to the right of the cam dog 122. When the slide 78 is moved to the left as the carriage approaches the end of its return movement, the pin 118 engages an inclined face 129 of the cam dog and depresses said dog which bypasses the pin and when the slide comes to rest with the projection 95 on the slide in engagement with the stop 97, the pin 118 is engaged between the cam face 116 on the cam carrier and the cam face 124 on the cam dog as shown in Fig. 5. When the slide 78 moves to the right upon the first escapement of the carriage, the engagement of the pin 118 with the cam face 124 on the cam dog lifts the actuator dog 74 to carry the pin 72 out of engagement with the lever 68 thereby releasing the line space mechanism.

The machine illustrated in the present application is provided with an electric driving motor 130 conveniently mounted on the bracket 132 secured to and projecting rearwardly from the rear rail 10 of the line space frame with which it travels as shown in Foothorap Patent No. 1,904,127 referred to above (see Figs. 2 and 3). Upon the shaft 134 of the motor is fixed a worm 136 meshing with a worm wheel 138 having a friction clutch connection 140 with the carriage return countershaft 141 journaled in bearings on said bracket. The driving clutch member 142 of the carriage return clutch is secured to the shaft 141. The driven member 143 of said clutch is fixed to one end of a sleeve 144 rotatable and longitudinally movable on the shaft 141, upon which is mounted the relatively wide carriage return pinion 145 meshing with the teeth of the rack 146 secured to the carriage 20. When the motor is running, the carriage return drive mechanism is thrown into operation by moving the sleeve 144 longitudinally of the shaft 141 to

engage the driven member 143 of the carriage return clutch with the driving member 142 thereof and the carriage return drive mechanism is thrown out of operation when the carriage reaches a predetermined point in its return movement by moving the sleeve 144 longitudinally of the shaft 141 to disengage the driven member of the clutch from the driving member thereof. The sleeve 144 is moved longitudinally of the shaft 141 to engage and disengage the carriage return clutch by means of a carriage return bail and connections between the same and the sleeve having substantially the same construction, arrangement and mode of operation as the corresponding mechanism shown and described in the above Foothorap patent. The mechanism for shifting the carriage return bail to throw the carriage return mechanism into and out of operation and the mechanism for protruding the check stop 112 to different positions to engage selectively the arresters 106 and 108 preferably have the same construction, arrangement and mode of operation as the corresponding mechanisms illustrated and described in the copending application of Oscar J. Sundstrand, Serial No. 149,571 filed June 22, 1937.

The power actuated mechanism for moving the line space frame forwardly and rearwardly over the platen comprises driving connections between the shaft 14 and the shaft 141 for driving the shaft 14 in opposite directions. The means for driving this shaft 14 includes a control shaft 147 mounted in suitable bearings carried by the side members 8 of the line space frame and by the bracket 132 and having a pinion 148 fixed thereto which meshes with a gear 149 secured to the shaft 14. The drive mechanism is controlled to drive the shaft 14 in opposite directions by shifting the control shaft 147 in opposite directions longitudinally in its bearings, the pinion 148 being a wide pinion to maintain constant mesh between said pinion and the gear during the longitudinal movement of said shaft.

The mechanism for driving the control shaft comprises a double faced clutch member 150 fast on the control shaft near its inner end and arranged to engage alternatively two coating oppositely facing clutch members (not shown) secured respectively to the opposed beveled gears 151 and 152 loose on the control shaft and in constant mesh with a crown gear 153 fast on the forward end of a countershaft 154 journaled in suitable bearings carried by the bracket 132 and arranged below and substantially parallel with the carriage return shaft 141. A gear 155 attached to the countershaft 154 adjacent its rear end meshes with a gear 156 secured to the rear end of the carriage return shaft 141.

The control shaft 147 is moved in opposite directions to engage the driving mechanism to cause said shaft to be driven either forwardly or rearwardly by means of knee levers 162 and 164 secured respectively to rock shafts 166 and 168 mounted in bearings attached to the platen frame of the machine. The movement of either of the knee levers rocks its shaft and with it an arm 170 fast on the shaft near its rear end, one of which arms is embraced between spring connected centering members 172 loose on the shaft and tending to maintain each of the shafts at an intermediate point between its limits of travel through the engagement of said members with a stud 174 fixed to the platen frame. The pivoted members 172 also engage the pin 176 secured in the adjacent arm 170 thereby maintaining the

arm centered with relation to the pin 174 on the frame. A link 178 connects the two arms 170, and a second link 180 connects one of the arms with an arm fixed to a rocker 182 pivoted at 184 upon brackets projecting laterally from the platen frame. Mounted on upwardly projecting arms on this rocker is a bail 186 forming a rail along which rolls a peripherally grooved wheel 188 loose on the axially shiftable control shaft 147, but held from axial movement relatively thereto.

The knee levers 162 and 164, when rocked outwardly, respectively, shift the control shaft 147 axially in opposite directions to engage one or another face of the double clutch 150 with the proper coating clutch member on bevel gears 151 and 152 to cause the motor to drive the traction shaft 14 and the traction gears 149 in one direction or the other and advance or retract the line space frame and the key carriage relatively to the operator seated in front of the machine.

When the line space frame is in operating position on the side rails of the platen frame, the control shaft 147 is held in central position by means of the pivoted centering members 172.

In order to hold said shaft in central position when the line space frame is lifted from the platen frame, as is often done for certain purposes, a second centering device acting directly on said shaft is provided. To this end a collar 190 is fixed to the control shaft 147 and is provided with a radially extending flange 192 which engages in a slot in the rearwardly extending arm of the centering lever 194 pivoted on a stud 196 secured in a bracket 198 mounted on the line space frame. A pin 200 attached to the forwardly extending arm of said lever projects upwardly through a slot in the bracket 198 and is engaged upon opposite sides thereof respectively by the forwardly extending arms of the bell crank levers 202 also pivoted on the stud 196. These bell crank levers are acted upon by the respective coiled springs 204 which tend to maintain the same in engagement with the pin 200. The said arms of these bell cranks are also arranged to engage the opposite sides of a fixed pin 206 projecting upwardly from the bracket 198.

The position of the cam carrier 114 about the shaft 62 is controlled by the position of the lever 194 which in turn is controlled by the position of the control shaft 147. The connections between the lever 194 and the cam carrier comprise a bell crank lever 208 pivoted on a stud 210 secured in the line space frame and a link 212 connecting one arm of the bell crank with the forwardly extending arm of the lever 194. The bell crank lever 208 is provided with a slot 214 in the other arm thereof, in which engages a pin 216 secured in an arm 218 adjustably fixed to the cam carrier, by means of a bolt 220.

Through the connections described, when the power actuated mechanism for moving the line space frame is out of operation, the cam carrier is held substantially in the position shown in Figs. 1 and 4. Assuming that the parts are in the positions shown in Fig. 5, as at the end of a return movement of the carriage, when the control shaft 147 is moved to the right to throw in the power mechanism to move the line space frame forwardly, the cam carrier is swung in a clockwise direction about the shaft 62 and the actuator dog 74 is swung upwardly by the engagement of the cam face 116 on the cam carrier with the pin 118 to break the connection between the slide 78 and the lever 68 as shown in Fig.

10. When the control shaft 147 is moved to the left to throw in the power mechanism to move the line space frame rearwardly, the cam carrier 114 is swung in a counterclockwise direction about the shaft 62 and the actuator dog 14 is swung upwardly to break said connection by the engagement of the cam face 124 on the dog 122 with the pin 118.

It is to be understood that the invention is not limited to the form thereof illustrated and described in this application or to the particular construction and arrangement of parts in which it is shown as embodied but that the invention may be embodied in other forms and may include other constructions within the scope of the 15 claims.

Having explained the nature and object of the invention and having illustrated and described a construction embodying the invention in its preferred form, what is claimed is:

1. A record making machine, having in combination, a carriage movable in opposite directions across the machine, a device movable in the direction of movement of the carriage and held substantially stationary during the greater part of the carriage movements and actuated by the carriage during its return movement, line space mechanism, releasable connections between said device and the line space mechanism for operating the line space mechanism from the movement of said device produced by movement of the carriage, said connections being held in operative condition at the end of the return movement of the carriage, power means for operating the line space mechanism and means for releasing said connections to release the line space mechanism upon throwing in said power means.

2. A record making machine, having in combination, a carriage movable in opposite directions across the machine, line space mechanism, means for actuating the line space mechanism from the return movement of the carriage comprising a breakable connection held in operative condition at the end of the return movement of the carriage, a cam-carrying member movable in opposite directions and cams carried by said member to break said connection respectively upon movement of said member in either direction and thereby release the line space mechanism.

3. A record making machine, having in combination a carriage movable in advance and return directions, line space mechanism, means for actuating the line space mechanism from the movement of the carriage comprising a breakable connection, power means for driving the line space mechanism forwardly or rearwardly alternatively, mechanism for throwing said power means into operation, a cam-carrying member movable in opposite directions, cam means carried by said member to break said connection upon movement of said member in either direction and mechanism for moving said cam-carrying member in one direction when the power means is thrown in to drive the line space mechanism forwardly and for moving said member in the opposite direction when said power means is thrown in to drive the line space mechanism rearwardly.

4. A record making machine, having in combination, a carriage movable in advance and return directions across the machine, line space mechanism, means for actuating the line space mechanism from the movement of the carriage

during the return of the carriage comprising a breakable connection, power means for driving the line space mechanism alternatively in opposite directions, mechanism for throwing said power means into operation, a device for breaking said connection and means for holding said device stationary during the first part of the advance movement of the carriage to break said connection and for actuating said device in one direction to break said connection upon the throwing in of the power means to drive the line space mechanism forwardly and for actuating said device in the opposite direction to break said connection upon the throwing in of the power means to drive the line space mechanism rearwardly.

5. A record making machine, having in combination, a carriage movable in opposite directions across the machine, line space mechanism, mechanism actuated in one direction to operate the line space mechanism from the return movement of the carriage comprising a breakable connection, means for actuating the latter mechanism in the opposite direction during the advance of the carriage, a movable cam carrier having cams for actuating said connection to break the same upon movement of said connection produced during the advance movement of the carriage or upon movement of said cam carrier in either direction, power means for actuating the line space mechanism to drive the same alternatively in opposite directions and mechanism for moving said cam carrier in one direction as said power means is thrown in to drive the line space mechanism forwardly and for moving said cam carrier in the opposite direction as the power means is thrown in to drive the line space mechanism rearwardly.

6. A record making machine, having in combination, a carriage movable in advance and return directions, line space mechanism, means actuated in one direction from the carriage during its return movement for operating the line space mechanism and comprising a breakable connection, mechanism for actuating said means in the opposite direction during the first part of the advance movement of the carriage, a device having two cams one for breaking said connection upon the advance of the carriage or upon movement of said device in one direction and the other for breaking said connection upon movement of the device in the opposite direction, power operated means for moving the line space mechanism in opposite directions and means for holding said device stationary during the first part of the advance movement of the carriage to cause said first cam to break said connection, for moving said device in one direction, upon the throwing in of the power means to drive the line space mechanism forwardly, to cause one of said cams to break said connection and for moving said device in the opposite direction upon the throwing in of the power means to drive the line space mechanism rearwardly to cause the other of said cams to break said connection.

7. A record making machine having, in combination, a carriage movable in opposite directions across the machine, a draft rod extending transversely of the machine, a contact device connected with one end of the draft rod, a contact device connected with the carriage for engaging said first contact device during the latter part of the return movement of the carriage, a slide connected with the opposite end of the draft rod 70 for movement therewith, a contact lever pivoted

on the slide, a contact arm arranged to be engaged and moved by said lever, line space mechanism, connections between the arm and the line space mechanism to actuate said mechanism from the movement of the slide and means for moving said lever out of position to engage said arm and thereby operatively disconnecting the slide from the line space mechanism.

8. A record making machine having, in combination, a carriage movable in opposite directions across the machine, a draft rod extending transversely of the machine, a contact device connected with one end of the draft rod, a contact device connected with the carriage for engaging said first contact device during the latter part of the return movement of the carriage, a slide connected with the opposite end of the draft rod for movement therewith, a contact lever pivoted on the slide, a contact arm arranged to be engaged and moved by said lever, line space mechanism, connections between the arm and the line space mechanism to actuate said mechanism from the movement of the slide, a pivoted cam lever mounted on an axis fixed with relation to the slide for moving said contact lever out of position to engage said contact arm and thereby operatively disconnecting the slide and the line space mechanism and means for controlling said cam lever.

9. A record making machine having, in combination, a carriage movable in advance and return directions across the machine, a longitudinally movable draft rod extending transversely of the machine, a contact device connected with one end of the draft rod, a contact device connected with the carriage and arranged to engage the first contact device to move the draft rod longitudinally during the return movement of the carriage, a slide connected with the opposite end of the draft rod for movement therewith, means for moving the draft rod and the slide with the carriage during the first part of the advance movement of the carriage, a contact lever pivoted on the slide, a contact arm arranged to be engaged and moved by the lever, line space mechanism, connections between the line space mechanism and the arm to actuate said mechanism, a movable cam-carrier, means for holding said cam-carrier fixed during the latter movement of the slide, power operated means for actuating the line space mechanism in opposite directions, means for moving said cam-carrier in one direction upon throwing in said power mechanism to drive the line space mechanism forwardly and for moving said cam-carrier in the opposite direction upon throwing in said power means to drive the line space mechanism rearwardly and cam means on the carrier for moving the contact lever out of position to engage said arm and thereby disconnecting the slide from the line space mechanism upon said movement of the slide while the cam-carrier is held fixed and upon movement of said cam-carrier in either of said directions.

10. A record making machine having, in combination, a carriage movable in opposite directions across the machine, line space mechanism, devices for stopping the carriage selectively in one of two or more predetermined return positions, means actuated in one direction from the carriage during its return movement to any one of said positions for operating the line space

mechanism comprising a releasable connection held in operative condition at the end of the return movement of the carriage, mechanism for actuating said means in the opposite direction during the first part of the advance movement of the carriage from any one of said positions, a device having a cam for releasing said connection during the latter movement of said means, power operated means for moving the line space mechanism, means for holding said device stationary during the first part of the advance movement of the carriage to cause said cam to release said connection and mechanism for moving said device in one direction to cause said cam to release said connection upon throwing in the power means to drive the line space mechanism.

11. A record making machine having, in combination, a carriage movable across the machine in advance and return directions, means for arresting the return movement of the carriage with the carriage in a predetermined position, a device movable in the direction of movement of the carriage and held substantially stationary during the greater part of the movements of the carriage, means for actuating said device from the carriage during the return movement of the carriage, line space mechanism, releasable connections between said device and the line space mechanism for actuating the line space mechanism from the movement of said device produced by the return movement of the carriage, said connections being held in operative condition at the end of the carriage return movement and mechanism rendered operative by the first part of the advance movement of the carriage from returned position for releasing said connections to release the line space mechanism.

12. A record making machine having, in combination, a carriage movable across the machine in opposite directions, line space mechanism, means actuated in one direction to operate the line space mechanism from the return movement of the carriage comprising a breakable connection, mechanism for actuating said means in the opposite direction during the first part of the advance movement of the carriage and a movable cam carrier having cams for actuating said connection to break the same upon movement of said connection produced during said advance movement of the carriage or upon movement of said cam carrier in either direction.

13. A record making machine having, in combination, a carriage movable in advance and return directions across the machine, line space mechanism, devices for stopping the return movement of the carriage selectively in one of two or more predetermined positions, means actuated from the carriage in one direction during the return movement of the carriage to any one of said positions for operating the line space mechanism comprising a releasable connection held in operative condition at the completion of the return movement of the carriage, mechanism for moving said means in the opposite direction during the first part of the advance movement of the carriage from any one of said positions and a device having a cam for releasing said connection upon the latter movement of said means or upon movement of said device in one direction.
